UNITED STATES PATENT OFFICE.

FRED T. LOVE, OF ROCKFORD, ILLINOIS, ASSIGNOR TO THE ROCKFORD SILVER PLATE COMPANY, OF SAME PLACE.

DESIGN FOR A HANDLE FOR SPOONS, &c.

SPECIFICATION forming part of Design No. 28,681, dated May 24, 1898.

Application filed February 5, 1898. Serial No. 669,285. Term of patent 7 years.

To all whom it may concern:

Be it known that I, FRED T. LOVE, a citizen of the United States, residing at Rockford, in the county of Winnebago and State of Illinois, have invented and produced a new and original Design for the Handles of Spoons, Forks, and Similar Articles, of which the following is a specification, reference being had to the accompanying drawing, forming a part thereof.

The drawing illustrates my design in its application to the handle of a spoon.

The leading or material features of my design consist in the vine-like scroll at or near the end of the blade of the handle, the scroll near the point where the blade joins the stem, the ornamental border at the sides of the blade, and the serrated ornamentation extending lengthwise of the stem.

In the drawing, A represents the bowl of the spoon, B the stem, and C the blade of the handle.

The bowl A is without ornamentation, the stem B is regular in its side lines, but has a double spray of sharp serrations B' depressed along its middle line, and the blade of the handle has the marking-plate C', the raised scroll C² on a plain ground at the point where the blade joins the stem, the ornamentations C³ C⁴, extending along the margins of the blade, and the vine-like scroll C⁵ at its upper end. All of said ornamentation except the serrated spray B' are in relief upon the surface of the handle.

Having thus described my invention, what I claim as new, and desire to secure by Letters Patent, is—

The design for a handle for spoons, forks, and similar articles, herein shown and described.

FRED T. LOVE.
